UNITED STATES PATENT OFFICE.

ARNAUD FOSTER, OF BAYONNE, FRANCE, ASSIGNOR TO HIMSELF, NIGEL ADOUR BEL-LAIRS, OF CHATEAU BISCARDY, ST. ETIENNE, FRANCE, AND HAMON D'ALBIN BEL-LAIRS, OF BIARRITZ, FRANCE.

DELIVERY CONTAINER.

Application filed January 11, 1926, Serial No. 80,592, and in France July 10, 1925.

This invention relates to delivery containers for various objects, and my improvement is particularly directed to a device of this character which is manipulable by one hand, said device having an oscillable element that can be turned by the fingers of the user's hand and will in its turning movement carry away from the container a single object and deposit it in the palm of the hand, 5 the oscillable element furthermore being adapted, upon release, to return automatically to its normal position.

The oscillable element is provided with a pocket or depression that in the normal position of said element lies at the base of the container in position to receive one of the contained objects in readiness for delivery, and said oscillable element is provided with 15 extended, cam-like means, capable of riding 20 through the lower portion of the container, to co-act with the forward wall of said container in guiding a contained object toward the pocket or depression of the oscillable element during the return movement of the 25 latter to its normal position.

Further my invention consists in the provision of means, carried by the oscillable element, and co-acting with the container wall, to serve as a stop for limiting the extent of rotation of said oscillatory element 30 in its object delivering movement, said stop means also serving to increase the weight, eccentrically applied to the oscillable element, to aid in restoring said oscillable element to its normal position.

Still further my invention includes the provision of means carried by the oscillable element and movable into the container in the delivery operation of the oscillable element, to prevent the creation of a clear space 40 between the cam-like extended means and the rear wall of the container which would otherwise tend to receive contained objects during the delivery operation and thereby 45 prevent the return movement of the oscillable element.

Other features and advantages of my invention will hereinafter appear.

In the drawing:—

50 Figure 1 is a front elevation of my improved delivery container.

Fig. 2 is a side sectional view thereof.

Fig. 3 is a side elevation.

Fig. 4 is a partial side section, enlarged,

showing the oscillable element in its normal 55 position.

Fig. 5 is a similar view, showing the oscillable element in the act of turning away from the container to deliver one of the objects.

Fig. 6 is a similar view, showing the oscillable element fully turned to effect delivery.

Fig. 7 is a front elevation of a modified form of my improved delivery container.

Fig. 8 is a perspective view, enlarged, of 65 the oscillable element employed in said modification.

Fig. 9 is a partial side section, enlarged, of 70 the modified device, showing the oscillable element in its normal position, and

Fig. 10 is a similar view, showing the oscillable element turned to effect delivery.

While not limited in its uses to any specific purpose, I have for example illustrated 75 my invention as directed to a delivery apparatus for cigarettes, operable with a single hand, so that, when fitted in a motor vehicle, the driver can easily obtain a cigarette without removing both hands from the steering wheel. Other uses to which the device 80 can be applied will be equally apparent.

In the views I have shown a container for cigarettes having the vertical front wall 1, the rearward wall 2 which is curved at its lower portion toward said front wall, and 85 the parallel side walls 3. Extended from the rear wall are lugs 4 by which the container may be secured to a suitable fixed support.

The lower ends of the front and rear walls 90 are in spaced relation, leaving a base clearance 5, to which is opposed the surface of an oscillable element, in the form of a cylinder 6, mounted on a shaft 7, that is journaled in pendent extensions 8 of the side 95 walls 3.

The container serves as a hopper for the objects to be delivered, such for example as cigarettes, and these are laid horizontally within the hopper, endwise between its sides.

100 The oscillable element is provided with a longitudinal surface depression or groove 9, of capacity enabling it to contain a single cigarette, said groove, in the normal position of the oscillable element, lying beneath the hopper in order that it may be supplied through the clearance 5.

105 Also the oscillable element 6 is provided

with means urging it in a clock-wise direction, as indicated by the arrow in Fig. 4, and a stop device 10 extended from the surface of said oscillable element is adapted to 5 coact with the front wall 1 of the container to limit the clock-wise rotation of the oscillable element, thereby holding the latter in its normal position with the groove 9 opposed to clearance 5.

10 In the operation of the device for the delivery of a cigarette the oscillable element is to be turned by finger pressure, in an anti-clockwise direction, the turning movement, shown in successive stages in Figs. 5 and 6, 15 bringing the palm of the hand underneath the device, in position to receive the cigarette as it falls by gravity from groove 9, see Fig. 6. Then, upon release of the oscillable element, it returns automatically to its 20 normal position, see Fig. 4.

The automatic return means for the oscillable element here shown consist in weighting said element more at one side its axis than at the other side. Thus, a pair of cam-like extensions or counterweights 11 are extended from element 6 at its right hand side, (in Fig. 4) thereby giving the preponderance in weight to that side. This condition may be accentuated by lightening the 25 element 6 at its left hand side (in Fig. 4) as by the removal of material indicated at 12.

The cam-like extensions 11 are adapted in the turning movement of the oscillable element to ride through slots 13 provided respectively in the rear and front walls 2 and 1 of the container, thereby enabling said extensions to displace the cigarettes upwardly from the hopper base in the anti-clockwise turning or delivery operation of the oscillable element. Also, since the cam-like extensions 11 merge peripherally into the perimeter 14 of groove 9, they are thereby enabled to serve as guides, in co-action with the front wall 1, directing one of the cigarettes (15) in the hopper into a downwardly forward position from which it may conveniently drop into the groove 9, as said groove passes thereunder in the automatic return movement of the oscillable element. 40 A still further function of said extensions consists in their holding upwardly the other cigarettes in the hopper while the cigarette (15) is being guided into a delivery position, thereby preventing a congested condition at 45 clearance 5 which would militate against the smooth and selective working of the delivery means.

The container may be provided with a cover 16 in the form of a receptacle for 50 ashes, and said cover may carry a rest 17 for a cigarette.

In the modified form of my invention shown in Figs. 6 to 9 the oscillable element 6 is shown as carrying a plate or wing 18 55 that lies lengthwise thereof and extends ec-

centrically therefrom at the side opposite the groove 9, to thereby augment the weight applied by the cam-like extensions 11 for more positively turning the oscillable element to its normal position shown in Fig. 8; 70 said wing 18 also serving as a stop, by co-action with the rear wall 2 of the container, to limit the extent of rotation of the oscillable element in its delivery operation.

Extended from the plate or wing 18, about 75 midway of its length, is a lug or projection 19, which may be rectangular in shape, and is adapted to enter the container through a slot 20 provided in its rear wall.

The location of this lug or projection 19 upon the oscillable element is to the rearward of the crowns of the cam-like extensions 11; and its function is to follow said extensions 11 into the container during the delivery operation of the oscillable element, to thereby occupy the space which occurs between the crowns of extensions 11 and rear wall 2, thereby preventing the entry into such space of the contained cigarettes or other objects. Otherwise the cigarettes or other objects 90 would lodge in such space and form an obstruction preventing the gravity-return of the oscillable element to its normal position.

Variations within the spirit and scope of my invention are equally comprehended by 95 the foregoing disclosure.

I claim:

1. A delivery device comprising an object containing hopper having front and rear walls provided with vertical slots at their lower ends, an oscillable cylinder mounted at the base of said hopper, said cylinder being manually turnable in one direction and provided with an object receiving groove that lies uppermost in the normal position of said cylinder, a cam-like counterweight extended from said cylinder to turn it in the return direction, and a stop to limit such return movement, said cam-like counterweight, in the manually operated movement of the cylinder, riding into the hopper through the slots in its walls and selectively guiding an object therein to a position for deposit in the cylinder groove. 105

2. A delivery device comprising an object containing hopper having front and rear walls provided with vertical slots at their lower ends, an oscillable cylinder mounted at the base of said hopper, said cylinder being manually turnable in one direction and provided with an object receiving groove that lies uppermost in the normal position of said cylinder, spaced cam-like projections extended from said cylinder that ride into the hopper through the slots in its walls to selectively guide an object therein into position for deposit in the cylinder groove, and a wing extended lengthwise from the cylinder, opposed to the groove therein, to serve as a return, counterweight therefor, said 110 120 125 130

wing also serving as a stop to limit the manually turnable movement of said cylinder.

3. A delivery device comprising an object containing hopper having front and rear walls provided with vertical slots at their lower ends, an oscillable cylinder mounted at the base of said hopper, said cylinder being manually turnable in one direction and provided with an object receiving groove that lies uppermost in the normal position of said cylinder, spaced cam-like projections

extended from said cylinder that ride into the hopper through the slots in its walls to selectively guide an object therein into position for deposit in the cylinder groove, and a rectangular projection extended from such cylinder to enter the hopper through a slot in its rear wall and prevent the lodgment of objects between the cam-like projections and said rear wall.
